UNITED STATES PATENT OFFICE.

ANDREW G. ANDERSON, OF CLAY CENTER, NEBRASKA.

CIRCUIT-CLOSER.

1,107,013.

Specification of Letters Patent.

Patented Aug. 11, 1914.

Application filed October 30, 1913. Serial No. 798,382.

To all whom it may concern:

Be it known that I, ANDREW G. ANDERSON, a citizen of the United States, residing at Clay Center, in the county of Clay and 5 State of Nebraska, have invented certain new and useful Improvements in Circuit-Closers; and I do declare the following to be a full, clear, and exact description of the invention, such as will enable others skilled 10 in the art to which it appertains to make and use the same.

This invention broadly relates to circuit closers but more particularly to that class of the latter intended to be used in conjunction with systems employed to electrically 15 light the headlights of automobiles.

One object of my invention is to provide a device of this character adapted to be used in conjunction with systems employed 20 for electrically lighting automobile headlights and which will enable the driver to control the individual circuits of each lamp.

Another and further object of my invention is to provide a circuit closer which 25 is simple, inexpensive and readily applicable to the dash board of any automobile.

With these and other objects in view, my invention consists of certain novel features of construction, and combination and arrangement of parts as will be more fully 30 described and claimed.

In the accompanying drawings in which similar reference numerals indicate corresponding parts, Figure 1 is a diagrammatic 35 view illustrating the application of my improved circuit closer to an electric lighting system employed in conjunction with the headlights of an automobile. Fig. 2 is an enlarged front elevation of a portion of the 40 dash board showing the two circuit closers and, Fig. 3 is a vertical section taken on the line 3—3 of Fig. 2.

In Fig. 1 of the drawings is diagrammatically shown the construction I preferentially employ, wherein the automobile A has the usual gasolene engine E with its magneto M and coil box C and the head lights or lamps L receive their gas from a tank T through a pipe P which in the present instance is controlled by a valve V adjacent the hand of the driver. I would locate this valve in such position that he may reach it without leaving his seat, and the detailed construction of the valve itself is not important. Obviously the tank might be replaced by an acetylene generator or other de-

vice for supplying an illuminating fluid to the burners within the lamps. These burners also I need not illustrate, nor the electrical gas-lighting devices themselves, as 60 both are well known in the art.

Coming now to the details of the present invention, I connect a bar 1 with one of the secondary wires in the coil box C, and this bar forms one pole of two push buttons. 65 The other wire 2 from either push button leads directly to the lighting device 3 in one of the lamps, which device will have two terminals adjacent the burner, and the other terminal will be connected with the 70 ground in any suitable way. The wire 2' leading from the other push button is connected with the lighting device 3' in the other lamp, entirely separate from the first-named wire. Each push button has a spring 75 tongue 4 whose free end underlies the bar 1 and whose other end is secured with a base 5 by a binding post 6 from which the wire 2 is led. At about its midlength the tongue is pierced with a hole through which extends a headed pin or screw 7 around which is coiled an expansive spring 8. The upper end of the spring is engaged beneath the head of the pin, and the lower end rests on a leaf spring 9 which overlies the tongue 80 4, and the presence of this leaf spring as well as of the coil spring gives the tip of the tongue great flexibility. The shank 10 of the knob passes loosely through a hole in a guard 11 secured to the front face of the 90 base 5, and is then reduced and shouldered as at 12, its smaller end 13 passing through a hole 14 in said base and standing over or near the tip of the tongue 4. Said hole is enlarged at its upper portion so as to produce a shoulder 15 within its length, and coiled on the reduced portion of the shank between this shoulder in the hole and the shoulder on the shank is an expansive spring 95 17. Finally a pin 18 passes through the 100 larger portion of the shank beneath the guard 11 and prevents the expansive force of this spring from throwing the shank out of place. As the knob is pressed upon its shank moves through the hole in the guard, the 105 expansive coiled spring is compressed within the enlarged upper end of the hole through the base, and the reduced lower end of the shank is projected out the lower end of said hole and bears upon the spring 110 tongue 4. When now the driver desires to light the lamps, he opens the valve V to

permit gas to pass from the tank T to the lamps L, and then he pushes first one push button and then the other. Closure of either circuit causes a spark to jump the spark gap in each lamp, and the lights are ignited at the points 3 and 3'.

From the foregoing it will be seen that I have provided a circuit closer of few parts any of which may be readily replaced when broken or worn and one which can be quickly and conveniently set up wherever desired.

Various changes in the form, proportion and the minor details of construction may be resorted to without departing from the principle or sacrificing any of the advantages of the claimed invention.

What is claimed as new is:

1. The herein described duplex push button comprising a base, a bar overlying the base and forming one terminal, a plurality of tongues lying on said base with their free ends beneath said bar, binding posts constituting the other terminals and securing the other ends of said tongues to said base, headed pins rising from the latter, the tongues having holes loosely embracing the pins, coil springs surrounding the pins beneath their heads, leaf springs overlying the tongues and standing against the other ends of said coil springs, and knobs whose shanks are slidably mounted through said base adjacent the free ends of said tongues.

2. The herein described duplex push button comprising a base, a bar overlying the base and forming one terminal, a plurality of tongues lying on said base with their free ends beneath said bar, binding posts constituting the other terminals and securing the other ends of said tongues to said

base, headed pins rising from the latter, the tongues having holes loosely embracing the pins, coil springs surrounding the pins beneath their heads, leaf springs overlying the tongues and standing against the other ends of said coil springs, knobs whose shanks have reduced portions passing through said base and standing over the free ends of the tongues, a guard having holes loosely receiving the shanks beneath the knobs, and pins through said shanks underlying the guard, for the purpose set forth.

3. In a push button, the combination with a base pierced with a hole enlarged at its outer end, a bar underlying the base and forming one terminal, a spring tongue also underlying the base and having one end overlying and out of contact with the bar, and a binding post securing the other end of the tongue to the base and constituting the other terminal; of a guard overlying the base and pierced with a hole, and a knob whose shank projects loosely through said hole and is shouldered and reduced, the reduced portion projecting through the hole in the base and standing over the free end of the tongue, and coiled expansive springs surrounding said reduced portion beneath the shoulder on the stem and within the enlarged upper end of the hole in said base.

In testimony whereof I have hereunto set my hand in presence of two subscribing witnesses.

ANDREW G. ANDERSON.
